UNITED STATES PATENT OFFICE.

WILLIAM W. WELCH, OF LIVERMORE, CALIFORNIA.

SCRAPER.

Application filed March 11, 1926. Serial No. 94,017.

This invention relates to scrapers and especially adapted for grading highways and the like.

The principal object of the invention is to provide a device of this character having a scoop for cutting, leveling and retaining the dirt and means to operate the scoop for dumping the load.

Another object of this invention is the provision of means for retaining the scoop in three different positions.

Other objects of the invention will appear as the disclosure progresses. The drawings are intended merely to indicate a possible embodiment of the invention. It is obvious that the actual needs of manufacture may necessitate certain mechanical changes. It is therefore not intended to limit the invention to the embodiment illustrated but rather to define such limits in the appended claims.

For a more detailed understanding of the invention, attention is now called to the drawings in which a preferred embodiment is shown illustrated. In these drawings like parts are designated by like reference characters in all the views.

Fig. 1 is a side view of the scraper.

Fig. 2 is a top view thereof.

Fig. 3 is a section on line 3—3 of Fig. 2 showing the scoop in a cutting position.

Fig. 4 is a similar view as Fig. 3 with the scoop shown in a dumping position.

Fig. 5 is a section on line 5—5 of Fig. 2.

Fig. 6 is a section on line 6—6 of Fig. 1.

Figs. 7 and 8 are details. Referring now to the drawings in detail in which like reference characters denote like parts throughout the specification, numeral 1 designates the frame, 2 the wheels 40 and 3 the axle. Attached to the frame are a pair of guides 4 having slots 5 therein. Adapted to move between the guides is a scoop 6 supported on a bar 7 which moves in the slots 5.

Numeral 8 represents a pair of lower catches having two grooves 8^a and 8^b for the reception of the bar 7 and numeral 9 designates an upper catch having a groove 10 for the bar 7 to fit into. See Figs. 7 and 8.

At the sides of the scoop and adapted to support same are upper and lower bars 11 and 12. The lower bar is pivoted to the lower part of the scoop and the axle 3 and the upper bar is pivoted to the upper part 55 of the scoop at one end and the other end to a forked element 13 (see Figs. 5 and 6).

Fastened to the upper and lower cross bars 14 and 15 are arms 16 and 17 connected together by a rigid link 18. A spring 19 is provided to normally urge the link downward.

As noted in Figs. 1 and 6, keyed to the axle 3 is a ratchet 20 co-operating with a pawl 21 and urged in contact with each other by a spring 22. In Fig. 5 is shown another ratchet 23 keyed to the shaft 3 and adapted to revolve between the forked elements 13. Pivoted to this element is a pawl 24 normally urged out of engagement with the ratchet 23 by the spring 25.

The load carrying position of the scoop is shown in Fig. 1. For cutting and scraping the dirt the scoop is raised in the position shown in Fig. 3 by the following means. It will be seen in Fig. 5 that when the cord 27 is pulled by the operator the pawls 24 will engage the ratchets 23. As the ratchets are keyed to the axle 3 the clockwise movement of the axle and the ratchets will partly revolve the forked elements 13, pull the bars 11 and raise the scoop supporting bars 7 upward from their former resting place in the grooves 8^a of the lower catches 8 to the new resting place 8^b of the catches 8. When the scoop has reached the desired position the cord 27 is released.

For dumping the load the cord 27 is pulled again and the scoop supporting bar 7 will rise by the aid of the means heretofore described through an arc and be guided by the slots 5 until the bar 7 will automatically catch in the grooves 10 of the upper catches 9 and be kept there until released. As soon as the bar is properly supported the cord 7 is released. The dumping position of the scoop is shown in Fig. 4.

For releasing the scoop supporting bar from any of its set positions the cord 28 is pulled by the operator. This will cause the bar 14 to revolve clockwise and as the catches 9 are keyed to the bar they will be raised and allow the scoop supporting bar to slide downward.

In the event that it is desired to allow the scoop to move down to its lowest position as shown in Fig. 1 when the scoop is set in the position shown in Fig. 3 the cord 28 is pulled, and as the arm 17 is connected to the arm 16 by the link 18 the arm 17 will swing the lower catch 18 on its pivoting bar as shown in Fig. 4 and allow the scoop to fall downward.

The ratchet 23 is keyed to the axle and revolves with same. The axle is adapted to revolve with the wheel when going forward and be stationary when moving backward. The mechanism to bring about this result consists of the ratchet 20 which is keyed to the axle, a pawl 21 and a spring 22.

Having thus described the invention what I desire to secure by United States Letters 10 Patent is:

1. In a device of the class described in combination, a frame, an axle, a pair of wheels, guides attached to the said frames, slots in the said guides, a cross bar adapted 15 to move in the said slots, a scoop supported by the said cross bar, an upper catch, a lower catch, means for releasing the said catches, a ratchet keyed to the said axle on the outer side of the said wheels, a pawl and spring 20 attached to the said wheels, the said ratchet and pawl adapted to co-operate for turning the axle when the said wheels move forward,

another ratchet and pawl, the last mentioned ratchet and pawl adapted to co-operate for raising and partly turning the scoop.

2. In a device of the class described in combination, a scoop, the said scoop adapted to swing on a cross bar, the said cross bar movable in a pair of slots of a pair of guides, latches at the upper and lower ends of said 30 slots, an axle, a lower bar pivoted to the said axle and lower part of said scoop, an upper bar having one end pivoted to the upper part of said scoop and the other end pivoted to a forked element, the said forked 35 element being loosely mounted on the said axle, a ratchet keyed to the said axle between the said forked element, a pawl adapted to engage the said ratchet, the said scoop adapted to be raised and partly turned when 40 the said ratchet and pawl co-operate.

In testimony whereof I affix my signature.

WILLIAM W. WELCH.
